Patented May 11, 1920.

UNITED STATES PATENT OFFICE.

RALPH C. COX, OF WAUNETA, NEBRASKA.

ROAD-GRADER.

1,339,548.

Specification of Letters Patent. Patented May 11, 1920.

Application filed March 22, 1919. Serial No. 284,240.

To all whom it may concern:

Be it known that I, RALPH C. Cox, a citizen of the United States, residing at Wauneta, in the county of Chase and State 5 of Nebraska, have invented certain new and useful Improvements in Road-Graders, of which the following is a specification, reference being had to the accompanying drawings.

10 This invention relates to road graders, and particularly to road graders of that type wherein a transversely extending blade is mounted upon a "circle" carried by a wheeled frame, the circle being vertically adjustable to control the depth of cut made by the blade or scraper.

My invention has to do particularly with the form of the scraper blade and its mounting, and the object of the invention is 20 primarily to provide a blade which is so shaped that it may be adjusted either to scrape over a flat surface or to flatten a road surface, or which may be adjusted to give greater or less crown to the road surface.

25 A further object is to so mount the blade that it may be readily adjusted, as above referred to, and so that the angle of the blade to the line of draft may be changed to thereby cause the earth which has been 30 scraped by the blade to be shifted or crowded toward one end of the blade and away from the other end and discharged at the end of the blade.

35 A further object is to so form and mount the blade that it may be used for cutting a ditch through the side of the road and elevating the earth from the ditch to, and distributing it over the surface of the road, and in this connection to so form the blade 40 that it will have a greater length of contact with the road surface than is possible with straight blades, and that it shall materially reduce the side draft on the machine.

45 My invention is illustrated in the accompanying drawings, wherein:—

Figure 1 is a side elevation of an ordinary form of road machine or scraper provided with my improved blade;

50 Fig. 1^a is a fragmentary vertical sectional view through the circle 17 showing the means whereby the circle is rotated;

Fig. 2 is a front elevation of the blade when the blade is set so as to crown the 55 road, and showing the circle in elevation;

Fig. 3 is a top view of the blade shown in Fig. 2;

Fig. 4 is an enlarged sectional view of the blade and a portion of the supporting beam therefor, showing the means for angularly adjusting the blade; and

Fig. 5 is a top plan view of a road drag with my blade applied thereto.

In the improved blade which forms the particular subject matter of this application, and as illustrated particularly clearly in Figs. 2 and 3, this blade is longitudinally curved on the arc of a circle, as shown in Fig. 3, that is the blade 10 is rearwardly bowed and the lower or cutting edge 11 of the blade, as shown in Fig. 2, is upwardly curved from its ends toward its middle, if this blade be held in an approximately vertical position. It will be obvious that by depressing the middle portion of the blade, 75 that the blade will be rocked upon its extremities, as upon a fulcrum, and that the middle portion of the blade will be lowered relative to the ends so that the cutting edge of the blade will rest flat upon the ground, 80 that is the entire cutting edge from end to end will be in the same horizontal plane. If, on the other hand, the middle of the blade is raised from this last named position, the middle of the cutting edge of the blade will 85 be lifted off the ground or other surface, or will be farther from the ground or other surface than the ends of the blade, and that under these circumstances, if the blade be used as shown in Fig. 2, it will crown the 90 road or fit the transverse curvature thereof, as illustrated particularly in Fig. 1. In order to secure the proper angular adjustment of the blade, I pivotally support the blade, as upon the beams 12, there being, as 95 illustrated in Fig. 2, two of these beams pivotally connected to the scraper blade, the lower ends of the curved rear portions of the beams being secured by an ear 13 on the blade, through which a pivot pin passes into 100 the curved end of the beam 12. Pivoted adjacent the upper edge of the blade are the latching members 14, shown as extending rearward past the beams and shown as being provided with notches 15 adapted to 105 engage with a pin 16 on the beam. By this means, it is obvious that the angle of the blade to the vertical may be adjusted and that the blade may be held latched in its adjusted position. As before stated, there 110

are preferably two of the beams 12 and these beams are mounted upon a circle 17 of any ordinary form, rotatably supported upon draft bars 18, which extend forward 5 and are pivotally secured to the forward end of the supporting frame 19 of the machine, shown in Fig. 1, so that the circle, the beams 12, and the scraper blade may be vertically adjusted. The rotation of the 10 circle 17 may be secured in any suitable manner such as is commonly used in this form of road machine, but I have illustrated for this purpose an adjusting shaft 20 having a pinion 21 engaging with an arcuate 15 rack on the circle 17. For the purpose of vertically adjusting the draft bars 18 and thus vertically adjusting the circle 17, I have shown bell crank levers 22^a mounted upon the frame of the machine and having 20 rack bars 23 engaged therewith, these rack bars being controlled by pinions 24 mounted upon suitable shafts and operated by means of a hand wheel 25. All of these parts are old and well known, and I have 25 merely illustrated a standard form of road machine, it being understood that any of the numerous standard forms of road machine might be used in place of the one illustrated and that the drawing is merely illustrative of one mounting for my improved 30 blade. By the means shown in Fig. 1, the blade may be rotated from a position at right angles to the line of draft to a position at less than a right angle to the line of 35 draft, and the blade may be raised or lowered as a whole or one end of the blade depressed and be left in its raised position. In other words, the blade is adjustable in the same manner as any other scraper blade. 40 In Fig. 5 I have illustrated my improved blade applied to a road drag of common form, two of these blades 10 being shown, disposed one behind the other, and connected by beams 26, the blades being set at 45 different angles by means of the shafts 27, one for each blade, each shaft being provided with a handle 28 moving over a rack and each shaft having at its opposite ends, arms 29 connected by links 30 to arms 31, 50 the equivalent of the arms 14 shown in Fig. 4, pivoted to the blade adjacent its upper edge. Any suitable draft devices are applied to this drag in the usual and well known manner and it is operated in the 55 same manner as an ordinary drag, but, as before stated, by adjusting the angle of the blades to a vertical plane, the cutting edge of the scraper blades may be so adjusted that the blades will conform to the crown 60 of a road or may be cut flat, that is cut over a level surface as distinguished from a crowned surface.

It will be obvious that if the bottom edge of a blade constructed as I have described 65 is disposed in a horizontal plane and the

scraper or grader is driven down the middle of a road in bad repair, that is a road which has been badly cut up after a rain, or badly rutted, the blade will act to surface the road and render it absolutely level. The blade 70 will cut off the high portions of the road and the curved blade will carry the loose dirt ahead in considerable quantities to fill depressions. If the middle of the blade is raised, and the machine driven down the 75 middle of the road, the same result will occur, except that the road will be crowned or the blade will conform to the crown of the road and the filling in the depressions will be rounded off in conformity to the 80 curvature of the road. If the blade be set at less than a right angle to the line of draft, scraped up dirt may be caused to travel from one end of the blade toward the other and dirt may be brought from the 85 margin or ditch side of the road toward the middle of the road. The ditch end of the blade may be set in deep and still carry the earth the full length of the blade.

It has been found in practice that this 90 form of blade mounted as illustrated in Fig. 1 is particularly effective for cutting a ditch at the side of the road and distributing the material over the road itself, and has many advantages over a longitudinally 95 straight blade having a straight lower edge. Such a straight blade, when disposed at the angle to a horizontal plane necessary to cut a ditch, has but little of its edge in engagement with the road surface and hardly 100 more than elevates the cut dirt from the ditch. A blade which is rearwardly bowed and has an upwardly curved, lower edge, when disposed at an acute angle to the line of draft and at an inclination to the horizontal plane, will deliver dirt from 105 12 to 18 inches farther from the ditch than will a straight blade of the same length, the reason being that the front end of the straight blade has to run nearly parallel with the 110 line of draft to keep it steady in the ground and also to start the earth traveling with the blade, and to prevent too much side draft. The straight blade set at this necessary angle delivers the dirt but a short distance toward the center of the grade, particularly during the first and second rounds, and this allows considerable of the scraped-up dirt to escape beneath the elevated end of the blade. A blade which is rearwardly 115 bowed and has its lower edge upwardly curved, as in my blade, permits the cutting end to be set at a particularly efficient angle, that is with its forward end nearly parallel with the line of draft, while the rear end of the blade is at such an angle that it will deliver the earth much farther upward on the crown of the road than otherwise possible. Inasmuch as the cutting edge is upwardly curved, the upward curvature 120 125 130

of this cutting edge may be increased relative to the road surface by tilting the top of the blade forward, and this permits the front of the blade to be depressed deeply in the ditch while the rear end is elevated to an extent which will not allow any portion of the earth to escape beneath the rear end.

Attention is particularly called to the fact that the shape of my improved blade practically eliminates or greatly reduces side draft, which is a serious problem in all machines of the side delivery type, and in cutting ditches, the side draft may be entirely eliminated. This is because the forward end of the acutely angled blade may be set parallel to the line of draft or even slightly past this point so that the back of the blade presses against the bank of the ditch and acts as a landside, while the remainder of the forward portion of the blade cutting the deepest in the hard earth is so nearly parallel with the line of draft that the side draft is almost nothing. This cannot be accomplished with a straight blade. It is also to be pointed out that the blade has a uniform, rearward bow and that its lower edge is uniformly curved upward so that a proper contour is given to the road surface and the road surface runs gradually down into the ditch and this gives to the ditch a rounded shoulder. This permits a vehicle to travel nearer to the ditch without danger, than it otherwise could. This is a decided constructive economy, particularly on relatively small roads where only a passing width is required and a deep drainage ditch is necessary.

By making the blade longitudinally curved, the cut dirt rolls backward along the inclined blade and the blade "scours" better, that is travels laterally more quickly than it otherwise would do. This also lightens the draft, as the better the "scour," the quicker the delivery and the lighter the draft. Pushing the dirt bodily forward means heavy draft. The rearward curvature of the blade and the upward curvature of the lower edge, with the adjustment for controlling the angle at which the blade is tilted, allows for either cutting a plain and flat surface or a surface of any desired crown, and it is possible by tilting the blade at an acute angle to the horizontal to even cut a concave contour, as for a shallow ditch, which is often desirable in road work. Furthermore, in maintenance work, the blade may be set straight across the road and easily and readily adjusted for the desired crown. Under these circumstances, it will reduce high centers and use the dirt so cut to fill ruts and low tracks usually found on each side of the high center. Inasmuch as the blade is rearwardly bowed, it will carry relatively large quantities of dirt from high points to depressions or mudholes.

Where the blade is used for a road drag, as illustrated in Fig. 5, the drag will not skid or move laterally on the crown of the road. A drag which is straight across the bottom and does not have an upwardly curved lower edge, or in which the blade is transversely straight instead of being rearwardly bowed, will tend to exaggerate the high center of the road, as it is impossible to keep such a drag on the top of a high center and going up one side of the center and back on the other side of the center will increase the peak at the middle of the road, and, as before pointed out, the blades, by reason of the fact that they are transversely bowed and have upwardly curved lower edges and are adjustable as to the angle of incidence, may be used either on perfectly flat roads or on a crowned road.

It will be noted from Figs. 1 and 4 that the blade 10 is slightly concave, that is is rearwardly curved or bowed from its upper to its lower edge. This curvature permits the blade to act somewhat in the manner of the moldboard of a plow when the blade is turned into an acute angle to the line of draft and tends to keep the dirt in advance of the blade more compressed, inasmuch as the dirt will roll up in front of the blade as the dirt moves laterally.

As I have before stated, I do not wish to be limited to any particular mounting for this blade or any particular adjustment for it, except mounting the blade so that it may be tilted to thereby cause the lower edge of the blade to be set so as to conform to any desired curvature of the road surface. Of course, it will be understood that the curvature of the blade as illustrated in the drawings is somewhat exaggerated in proportion to the size of the machine shown.

I claim:—

1. A scraping blade for road grading or scraping machines, said blade being bowed rearwardly and having its lower edge curved upward uniformly and continuously from its ends toward its middle.

2. In a road grading or surfacing machine, a rearwardly bowed blade having its lower edge curved upward uniformly and continuously from its ends to its middle, and means for pivotally supporting the blade for tilting adjustment in a vertical plane perpendicular to the blade, and means for holding the blade in its adjusted positions.

3. A road grading or surfacing machine having a scraping blade which is rearwardly bowed, the ends of the scraping blade extending forward and the lower edge of the blade being upwardly bowed from its ends toward its middle.

4. A road grading or surfacing machine having a rearwardly bowed scraping blade, the ends of which extend forward of the middle of the blade, the lower edge of the

blade being upwardly bowed uniformly and constantly from its ends toward its middle, the blade being tiltably mounted to adjustably vary the angle of the blade to a horizontal plane.

5. A road grading or surfacing machine having a blade uniformly bowed rearward from end to end, the ends of the blade being in advance of the middle of the blade, 10 the lower cutting edge of the blade being concavely curved uniformly from end to end, means for supporting the blade, and means for tilting the blade into different angular relations to a horizontal plane.

15. 6. A road grading machine including a wheeled supporting frame, a scraping blade rearwardly bowed from end to end, the lower edge of said blade being upwardly curved from its ends toward its middle, 20 means for supporting the blade upon the wheeled frame including means whereby the blade as a whole may be adjusted to various angles to the line of draft, means whereby the blade may be adjusted to raise one

end of the blade higher than the other, and 25 means whereby the blade may be tilted forward or rearward with relation to a transverse vertical plane and held in its adjusted position.

7. A road grading machine including a 30 wheeled supporting frame, a circle mounted below the frame for rotative movement and for vertical movement, manually controlled means on the frame for rotating said circle or vertically adjusting it, beams carried on 35 the circle and extending rearward therefrom and forwardly and downwardly curved at their rear ends, and a scraping blade rearwardly bowed from end to end and having its lower edge uniformly upwardly curved, said scraping blade being pivotally mounted upon the ends of said beams for tilting movement, and means for holding the scraping blade in tiltably adjusted positions.

40 In testimony whereof I hereunto affix my signature.

45 RALPH C. COX.
